UNITED STATES PATENT OFFICE.

THEODORE ATZENWEILER, OF HURON, KANSAS.

WRENCH.

No. 896,073.

Specification of Letters Patent.

Patented Aug. 18, 1908.

Application filed April 27, 1908. Serial No. 429,472.

To all whom it may concern:

Be it known that I, THEODORE ATZENWEILER, a citizen of the United States, residing at Huron, in the county of Atchison and State of Kansas, have invented certain new and useful Improvements in Wrenches, of which the following is a specification, reference being had to the accompanying drawings.

10 My invention relates to improvements in ratchet wrenches and consists of the novel features of construction and the combination and arrangement of parts hereinafter fully described and claimed.

15 The object of the invention is to improve and simplify the construction and operation of devices of this character and thereby render the same stronger, more durable and convenient and less expensive.

20 The above and other objects of the invention are attained in its preferred embodiment illustrated in the accompanying drawings, in which

Figure 1 is a plan view of my improved wrench; Fig. 2 is an edge view of the same; Fig. 3 is a view showing the cover plate removed and one of the pawls secured in an inoperative position; and Figs. 4 and 5 are detail views of two of the interchangeable socket 30 members for engaging the taps or nuts.

My improved wrench comprises a head 1 from one end of which projects a suitable handle 2. Said head comprises a solid body portion one side face of which is recessed, as at 3, to receive a removable cover plate 4 and the other side of which has formed integral with it an extension which forms a plate 5 similar to said cover plate. The portions of the plates or members 4, 5 which extend 40 beyond the body or solid portion of the head are circular in form and are provided with alined concentric circular openings 6 to rotatably receive the reduced ends 7 of a ratchet ring or collar 8 arranged for rotation between the plates 4, 5. This ratchet ring or member 8 has the outer face of its portion which projects between the plates 4, 5 formed with ratchet notches 9 to receive oppositely disposed pawls or dogs 10, 11, as presently explained. The removable cover plate 4 is secured to the head or body 1 by a screw 12 passed through its inner portion and into a

threaded socket in said head; and it serves to retain both the ratchet member or ring and the pawls in said head.

55

The pawls 10, 11 are of peculiar construction, each having a body portion 13 formed at one end with a circular pivot 14, at its other end with a tooth 15 to engage the notches 9 and at an intermediate point with an angularly projecting finger piece 16, the latter being formed with an inwardly extending projection 17. One of said pawls is provided upon each side of the head or body 1 so that they are oppositely disposed and in order to mount them in said head, the latter has formed in each of its side edges a circular socket 18 to receive the pivot portion 14, of one of the pawls and a recess or socket 19 to receive the projecting portion 17 of the finger piece of said pawl and a coil spring 20 which is confined between the bottom of said socket 19 and the portion 17 of the pawl and exerts its energy to project the finger piece outwardly and thereby swing the shouldered end or tooth 15 of the pawl inwardly into engagement with the ratchet member. It will be seen that when the finger piece 16 of each pawl is pressed inwardly the tooth 15 will be swung outwardly to free the ratchet member. By shaping the body or head 1 and constructing and mounting the pawl as shown, it will be seen that the wrench will be exceedingly strong and durable and also inexpensive since the parts may be produced at a small cost and quickly and easily assembled. When the cover plate 4 is removed the pawls may be readily removed by simply lifting them out of the sockets 18, 19 and when said cover plate is applied it will effectively retain them in the head without the use of pivot screws, or similar devices.

For the purpose of holding or locking one of the pawls in an inoperative position while the other engages the ratchet member I provide a locking sleeve or collar 21 which is slidably and rotatably mounted upon the handle 2 and formed with a projection or finger 22 which may be engaged with the finger piece 16 of either pawl to hold the same in its retracted position, as will be readily understood upon reference to Fig. 3. If desired, the finger pieces 16 may be notched or recessed, as at 23, to receive the projection 22

95

100

on the locking collar or member. I may also provide a pin 24 or any other suitable stop upon the handle 2 to limit the sliding movement of said locking collar and retain it upon the handle. Said stop is so positioned that when the locking collar is moved inwardly on the handle to engage it, the projection 22 will clear the head or body of the wrench so that said collar can be turned or rotated upon the handle to bring said projection into alignment with either of the pawls, thus when the collar is moved outwardly or toward the head 1 and the finger piece of such pawl is pressed inwardly the projection 22 may be engaged with the notch or recess 23 in the finger piece.

In order to adapt my wrench for engaging nuts, bolt heads, and the like of different sizes and shapes I provide for use in connection with it a plurality of socket members 24, 25 such as illustrated in Figs. 4 and 5 of the drawings. Each of these members has at its outer end a socket 26 which may be of any size and any shape. As shown in the drawings said sockets are square to receive square nuts or bolt heads and they are of different sizes. The other end of each of the socket members has a cylindrical portion adapted to enter a similar shaped opening 30 in the ratchet ring or member 8 and formed upon its outer face at one or more points with longitudinally extending ribs 27 adapted to enter grooves or channels 28 similarly shaped and similarly arranged in the opening in said ratchet member. Said socket members are retained in the ratchet member by means of a catch 29 in the form of a lever pivoted upon one of the ends 7 of the ratchet member and having at its free end a laterally projecting tongue adapted to swing into an opening in a keeper projection 30 on the end of said socket members, as clearly shown in the drawings. Said free end of the catch lever is also formed with an outwardly projecting finger piece, as shown more clearly in Fig. 2. It will be seen that by constructing these nut engaging socket members as described, they may be quickly applied to and removed from the wrench head so that the wrench may be quickly and easily adapted for the work to be done.

From the foregoing it will be seen that my wrench is exceedingly simple and practical in construction and will therefore be strong and durable in use and comparatively inexpensive to manufacture. It is also exceedingly convenient in operation since it permits nuts, bolts, or the like to be quickly and easily screwed or unscrewed. When the nut or bolt is to be rotated in one direction one of the pawls may be quickly secured in an inoperative position so that by oscillating the handle of the wrench the other pawl will ro-

tate the ratchet member in the proper direction, and that when it is desired to turn the nut or bolt in the opposite direction the locking member or collar is reversed to release one pawl and to hold the other in an inoperative position.

Having thus described my invention what I claim is:

1. A wrench comprising a head formed in its opposite edges with pivot sockets and with sockets arranged adjacent to said pivot sockets, said head being formed upon one side with an extension plate having a circular opening, a handle projecting from said head, a removable cover plate secured on the other side of said head and having a circular opening to align with the one in said extension plate, a ratchet member arranged between said plates and having portions mounted for rotation in the openings in said plates, means upon the ratchet member to engage a nut, oppositely disposed pawls to engage said ratchet member, each pawl having a pivot portion arranged in one of the pivot sockets in the head and a finger projection extending into one of the other sockets in said head, springs in the last mentioned sockets for actuating the finger pieces of the pawls outwardly and means for holding either of said pawls in a retracted position.

2. A wrench comprising a head formed in its opposite edges with pivot sockets and with sockets arranged adjacent to said pivot sockets, said head being formed upon one side with an extension plate having a circular opening, a handle projecting from said head, a removable cover plate secured on the other side of said head and having a circular opening to align with the one in said extension plate, a ratchet member arranged between said plates and having portions mounted for rotation in the openings in said plates, means upon the ratchet member to engage a nut, oppositely disposed pawls to engage said ratchet member, each pawl having a pivot portion arranged in one of the pivot sockets in the head and a finger projection extending into one of the other sockets in said head, springs in the last mentioned sockets for actuating the finger pieces of the pawls outwardly, and a locking collar slidably and rotatably mounted upon said handle and provided with a projection adapted to engage the finger piece of either of said pawls to hold the same retracted.

3. A wrench comprising a head having a handle projecting therefrom, a rotary ratchet ring in said head and formed with a central opening provided with a grooved wall, a pawl upon the head to co-act with said ratchet, a removable nut engaging socket member adapted to enter the opening in the ratchet and formed upon its side with a rib to enter

the groove in the wall of said opening and upon its end with the projecting apertured lug 30, and the catch lever 29 pivoted upon one end of said ring and having at its free end 5 a laterally projecting tongue to enter the opening in said lug and an outwardly projecting finger piece.

In testimony whereof I hereunto affix my signature in the presence of two witnesses.

THEODORE ATZENWEILER.
